INVENTOR

By R. J. McCarty.

ATTORNEY

UNITED STATES PATENT OFFICE.

CHARLES MACGREGOR, OF DAYTON, OHIO.

GALVANO-CAUTERY INSTRUMENT.

SPECIFICATION forming part of Letters Patent No. 595,573, dated December 14, 1897.

Application filed October 16, 1897. Serial No. 655,386. (No model.)

To all whom it may concern:

Be it known that I, CHARLES MACGREGOR, a citizen of the United States, residing at Dayton, in the county of Montgomery and State of Ohio, have invented certain new and useful Improvements in Galvano-Cauteries; and I do declare the following to be a full, clear, and exact description of the invention, such as will enable others skilled in the art to which it appertains to make and use the same, reference being had to the accompanying drawings, and to the figures and letters of reference marked thereon, which form a part of this specification.

15 My invention relates to improvements in galvano-cautery instruments and is embraced in the construction of the handle or the non-conducting piece in which the electrodes or conductors are mounted, which enables their 20 free manipulation in the hands of the physician or other person applying the instrument.

The object of the invention is to provide a handle and means therein for securing the inner ends of the disconnected conductor or 25 electrode to the end that the instrument will be more durable and less liable to become inoperative, owing to any liability of the electrode contact-pieces becoming loosened.

In the accompanying drawings, Figure 1 is 30 a view of the upper side of a galvano-cautery instrument constructed in accordance with my invention. Fig. 2 is a side elevation thereof. Fig. 3 is a view of the upper section of the handle, showing the electrodes therein 35 and the contact-blocks. Fig. 4 is a similar view of the lower section of the handle. Fig. 5 is an enlarged cross-section on the line $x-x$, Fig. 2. Figs. 6 and 7 are views showing modified means for preventing the electrodes from 40 turning in their seats.

The handle is preferably constructed of the non-conducting material known as "wood-fiber," is of rectangular form in cross-section, and consists of two sections 1 and 2, which 45 are securely united by means of screws. The inner side of section 1 is provided with longitudinal grooves 3 and 4, in which the electrodes or conductors 5 and 6 fit, the latter conductor being disconnected on the broken side 50 of the circuit. The inner ends of the broken electrode 6 are screwed into blocks 7 and 8 of conducting material, which fit into cavities

or recesses 9 and 10 in said section 1. The shapes of these cavities conform to the shapes of the blocks, so that the said blocks cannot 55 become displaced by any endwise pressure on the attached conductors 6. The said electrodes or conductors 5 and 6 are preferably square in cross-section in order to avoid any possibility of their turning in their seats in 60 the handle while the instrument is being manipulated. The cauterizing loop or wire 15 is secured to the electrodes by binding-screws 16 in a straight line or on an angle to suit the requirements of the cautery work to be 65 performed. The inner side of section 2 of the handle is provided with longitudinal grooves 11 and 12 and cavities 13 and 14, corresponding in shape to those in the other section and which are adapted to receive and 70 inclose the upper sides of the electrodes 5 and 6 and the blocks 7 and 8. In both sections of the handle the cavities which receive the blocks 7 and 8 have a wall a , of insulating material, left after their formation, which insulates the blocks from the continuous electrode 75 5, so that the possibility of induction or short-circuiting is avoided. When the parts of the handle are united, the contact-blocks are maintained in a fixed position in the handle, 80 and the electrodes being square in cross-section and fitting in corresponding grooves in the handle it will be apparent that any disconnection of the electrodes is impossible.

17 designates a circuit-closer of the ordinary spring type, having electrical connection with block 7 and adapted to be pressed into contact with a platinum contact-point 18 in electrical connection with block 8 to complete the circuit for work. The blocks 7 and 8 need 90 not necessarily be of rectangular form in order to prevent their disconnection with the ends of the broken electrode. Blocks of circular form will answer as well. The electrodes may be round in cross-section, and 95 means to prevent their turning in their grooves, such as disks or flanges 20, fixed thereto and provided with slits cut in the two parts of the handle, may be employed.

Having described my invention, I claim— 100

1. A galvano-cautery instrument comprising a two-part handle each of said parts provided with longitudinal grooves, and cavities therein, a continuous and a disconnected elec-

trode inclosed in said longitudinal grooves, contact-blocks loosely seated in said cavities, and having screw-threaded engagement with the inner ends of the disconnected electrode, and walls of insulating material between said blocks and the continuous electrode, as herein shown and described.

5 2. In a galvano-cautery instrument, the combination of a handle consisting of two 10 parts of non-conducting material each of said parts having angular cavities, and longitudinal grooves in their meeting sides, electrodes adapted to fit into said grooves, and angular

contact-blocks to which the inner ends of the disconnected electrode is affixed, the said 15 blocks being loosely inclosed in the cavities in said handle, and prevented from becoming detached from the ends of the electrode, as herein shown and described.

15 In testimony whereof I affix my signature 20 in presence of two witnesses.

CHARLES MACGREGOR.
